UNITED STATES PATENT OFFICE.

GEORGE RIESECK, OF ALLEGHENY, PENNSYLVANIA.

MEAT-CHOPPER.

SPECIFICATION forming part of Letters Patent No. 240,547, dated April 26, 1881.

Application filed July 29, 1880. (No model.)

To all whom it may concern:

Be it known that I, GEORGE RIESECK, of Allegheny, in the county of Allegheny and State of Pennsylvania, have invented certain new and 5 useful Improvements in Meat-Choppers; and I do hereby declare the following to be a full, clear, and exact description of the invention, such as will enable others skilled in the art to which it pertains to make and use it, reference being 10 had to the accompanying drawings, which form part of this specification.

My invention relates to an improvement in meat-choppers; and it consists, first, in placing the boxes for the cranked driving-shaft 15 upon a vertically-movable rod, and guiding the boxes in their movements by means of slots in the frame, and attaching the pitmen for operating the cutters, and the valve-rod to the cranked shaft, so that when the shaft is raised 20 upward the machine will be stopped; second, in the combination of the cranked shaft having a vertical movement, the pitmen which operate the cutters, the valve-rod and valve, which are operated by the shaft, a valve for controlling the admission of steam to the steam-chest, and which valve has a rod attached to 25 it for passing up through a frictional stuffing-box, with the tub, cutter, and frame; third, in the combination of the cranked shaft, which 30 is journaled upon a vertically-moving bar, connecting-links, and levers which are pivoted together at their inner ends and to the frame at their outer ends with the pitmen, cutters, and tub; fourth, in the arrangement and combination of parts, which will be more fully described hereinafter, whereby the driving mechanism is thrown in and out of gear with the 35 revolving rack upon which the tub is placed.

The accompanying drawings represent my 40 invention.

Figures 1 and 2 are side elevations of my invention. Fig. 3 is an inverted view of the same. Fig. 4 is a vertical section taken through the frame. Fig. 5 are detail views of the valves. 45 Fig. 6 is a side elevation.

The frame A consists of the standards a, braced by b, cast with the former, having braces b', b'', and b''' between them.

Between the sides of the frame A, near the 50 bottom, are the horizontal braces d, which sup-

port the meat-block B upon rollers in advance of the standards a.

Under the block B, and attached thereto, is a rack, x, that is engaged by a pinion, D, rotated by a pulley, E, on the end of its shaft, 55 outside of the frame A. The shaft of this pinion moves in a sleeve, e, to which a lever, f, whose fulcrum is on the inside of the frame A, is attached. The handle of the lever f extends forward, and if depressed raises the sleeve and 60 pinion, engaging thereby the rack under the meat-block; but when raised up it throws the pinion out of gear, whereby the rotation of the block is stopped.

Between the lever f and the inside of the 65 frame A is the guide x', with shoulders that limit the up or down motion of the lever; and pivoted on it is a dog, g, which, when the lever is depressed and the pinion in gear with the bevel-wheel, catches on top of a triangular 70 block, h, near the handle of the lever, and prevents it from rising; but when the pinion is thrown out of gear, by raising the lever the dog catches under the block h and secures it in that position. By this means the meat-block 75 may, for any purpose whatever, be stopped, turned back or forward, and again set in motion by hand while the engine is running.

In the standards a, between the braces b' and b'', are slots i, in which rest the ends of a flanged 80 bar, C, and under the slots, at the inside of the standards, are vertical guides K, in which the ends of the flange under the bar C are confined. On top of the bar, at its ends and in the middle, are pillow-blocks N, in which the 85 crank-shaft F is journaled. The ends of the crank-shaft protrude beyond the standards a, and on one of them is a belt that runs the pulley E', and on the other is the fly-wheel G.

The pitmen w on the crank-shaft are rigidly 90 attached by wrists to vertical rods l, that have their lower guides on a brace, m, between the standards, and at their upper ends to the slides n, in front of the upper cross-piece connecting the standards.

From the attachment of the pitmen to the 95 vertical rods l forward, extend the arms p at a right angle with the rods. The arms are supported by braces attached to the slides n, and to or near the outer ends of the arms p, 100

thus forming a rectangular triangle over the meat-block. The knives H are adjustably attached to the forward ends of the arms p, and are raised or depressed by the rotating crank-shaft.

- 5 One (or both) of the rods l is prolonged upward beyond the slides n, and acts as a piston-rod to the steam-cylinder P, placed on top of the upper brace, between the standards a.
- 10 At the side of the cylinder is a steam-chest, S, into which enters, from below, the valve-stem U, joined to a cam-rod on an eccentric of the crank-shaft F. The valve-stem U operates the sliding valve within the steam-chest in the usual manner.

15 Steam is admitted into the chest through a valve, q, attached to the chest, which valve is operated by the rod v, that is brought in contact with it when the crank-shaft is lifted up from its ordinary position.

20 On top of the valve q in the valve-chamber is a rod, r, which passes out through a stuffing-box, and holds the valve when it has been pushed up by the rod underneath the valve in that position. The steam is shut off when the valve is pushed up, and the friction on the rod in the stuffing-box keeps it from reopening itself, and will have to be pushed down by hand to readmit steam.

25 The valve q, with its rod r, may be placed in any position connected with the steam-chest, and operated in a similar manner to accomplish the same object, which is to shut off steam automatically when circumstances require it.

30 The flanged bar C, resting in the slots i, is raised from its seat when the regular motion of the crank is interrupted by an intervening object between the knives and the block—such as a bone or other hard substance—that resists the edge of the knives and would hinder the crank from passing to and over its center. At the same time the rod and valve-stem connected with the crank-shaft are raised up and the valve admitting steam is closed. Thus the

35 machine is brought to a standstill, when a continued motion would unavoidably cause some of its parts to be broken.

To prevent an oblique or unequal motion of the bar C when only one of the knives meets an impediment, a pair of links, t, are jointed to the flange under the bar, which links form fulerums to two levers, J, that are pivoted to the insides of the standards a. The ends of the levers meeting at the middle, under the bar C, are joined together, and by this device the motion of the bar, be it rising or falling, is made to be always horizontal.

The object of my invention is to prevent oil, grease, or dirt, from falling on the meat-block and being chopped with the meat, by placing all parts of the machinery employed to operate this meat-chopper away from over the meat-block. Many of the meat-choppers now in use have a great part of the working machinery immediately over the meat-block and knives, and it is consequently next to impossible to prevent things from becoming mixed in with the meat that should be kept separate from it. The automatic action of the valve, whereby the steam is cut off at a moment when continued motion would inevitably cause some part of the machine to be injured, I also consider of importance. An advantage is furthermore gained by the use of the lever and dog, since by stopping the rotating block access to it is obtained, whether to clean its surface or for other purposes.

Having thus described my invention, I claim—

1. In a meat-chopper, the combination of the frame provided with guiding-slots, the crank-shaft having its ends journaled in boxes which move in slots, the bar C, having the boxes or bearings for the shaft secured to its top, the pitmen for operating the cutters H, the slide-valve, valve q, the operating-rod v, and the tub in which the meat is cut, substantially as shown.

2. In a meat-chopper, the combination of the cranked shaft F, having a vertical movement, the pitmen w, for operating the cutters, and the valve-rod v, attached to the shaft, with the valve q, rod r, and stuffing-box, tub, cutters, and frame, the parts being combined to operate substantially as described.

3. In a meat-chopper, the combination of the links t, levers J, pivoted to the frame at their outer ends and to each other at their inner ends, with the vertically-moving bar C and shaft F, mounted thereon, pitmen, cutters, and tub, substantially as set forth.

4. In a meat-chopper, the combination of a revolving rack upon which the tub is placed, the pinion D, placed on the same shaft as the driving-wheel E', with the sleeve e, lever f, dog g, and guide x', substantially as shown.

In testimony that I claim the foregoing I have hereunto set my hand this 24th day of June, 1880.

GEORGE RIESECK.
